UNITED STATES PATENT OFFICE.

ALTON J. SHAW, OF MUSKEGON, MICHIGAN.

ELECTRIC RESISTANCE-CARD.

SPECIFICATION forming part of Letters Patent No. 534,699, dated February 26, 1895.

Application filed December 1, 1894. Serial No. 530,588. (No model.)

To all whom it may concern:

Be it known that I, ALTON J. SHAW, a citizen of the United States, residing at Muskegon, in the county of Muskegon and State 5 of Michigan, have invented certain new and useful Improvements in Electric Resistance-Cards, of which the following is a specification.

My invention consists in a novel construction of electrical resistances, as hereinafter set forth.

The invention is illustrated in the accompanying drawings, in which—

Figure 1 is a perspective view of a resistance card, block, or section, embodying my invention, the conducting body being represented in the form of a flat strip or band, and a portion of the device being broken away to better show the construction. Fig. 2 is a similar view, representing the conductor as made of wire; and Figs. 3 and 4 are detail views which will be hereinafter referred to.

The invention is designed to produce a simple, cheap and durable resistance device, capable of use alone, or as one of a group or series in a rheostat or current regulator.

In the drawings, A indicates a frame which is preferably of cast iron, and comprises three bars *a*, *b* and *c*, the bar *b* being channeled on 30 its inner face as shown in Fig. 3.

B indicates a conducting strip, which is preferably made of hoop iron or other suitable flat metallic tape or band folded back and forth upon itself, the several folds or layers 35 being separated one from another by strips *C* of micanite or other good insulating material. The ends of the folds and of the insulating strips *C* are covered or incased by strips *D* of mica, asbestos or other good insulating 40 material, mica being preferred because of its good insulating qualities and its proof against injury by heat or by electrical action.

The folded band with the interposed strips and with the covering strips *D* applied as 45 stated and as shown in Figs. 1 and 2, is inserted within the frame A in the manner indicated in Figs. 1 and 3, the lower strip or sheet *D* of insulating material fitting within the channel of the bar *b* of said frame.

50 The folds of the band *b* and the interposed

strips *C* are of such length that they, together with the upper or second strip or sheet *D*, come flush with the upper ends of the bars *a* and *c* of frame A. To retain the folded strip and the insulating strips in place, I apply to 55 the open side of frame A a sheet metal cap *E*, folded as shown in Figs. 3 and 4, to form a channeled plate or bar, the sides of which extend downward over the insulating strip *D* and over the folded ends of the strip *E* sufficiently to retain said parts in proper relation to the frame A.

The upper ends of the bars *a* and *b* are provided each with an opening *d*, and the cap or cover plate *E* is secured to said arms by forcing the metal of its side wings or flanges into said openings *d* by means of a punch or other suitable implement, in the manner indicated in Figs. 1, 2 and 4. This affords a cheap and 70 secure fastening and one which may, if necessary, be broken or destroyed to permit the removal of cap *E*.

It will be observed by referring to Fig. 1 that the first fold of the band *B* lies in immediate contact with the bar *a* of frame A throughout its length, so that good electrical contact is established between the frame A and the conductor *B* at that point, but owing to the insulation above described, electrical contact between the frame and the band is 80 prevented at all other points, and consequently if contact be made with the frame A at any point, a current can pass by band *B* only by traversing its entire length. The other end of band *B*, that is, the end opposite 85 that which is in contact with bar *a*, is provided with a metallic tongue or tab *e*, by which connection may be made with a second section or with a line or conductor as desired.

It would of course be possible, if less than 90 the entire resistance of band *B* be desired, to make contact therewith at a point between its ends and at one end, but this will not ordinarily be desirable, although for heavy currents when the resistance is low, the tongue 95 or tab *e* may advantageously be attached to the folded band at its center, the current being divided, one half going to each end of the folded band *B*. In this case, the first fold of the band at each end of the frame, will lie 100

in contact therewith, as hereinbefore described of one end only.

The frame A will be provided with suitably tapped holes F to receive screws or tap bolts 5 by which to fasten the frame A to a suitable support.

In Fig. 2 I have represented the conducting band B in the form of a wire, one end of which enters a hole in the end bar of frame 10 A, and is made fast therein by a wedge pin h, by soldering or otherwise. The wire in this case is wound about insulating strips C, similar to those shown and described in connection with Fig. 1, similar strips being also 15 interposed between those about which the wire is wound, to prevent folds of proximate wound strips from making electrical contact. In all other respects the construction is the same as shown and described in connection 20 with Figs. 1, 3 and 4, that is to say, the same insulating strips D and cap or cover plate E are used, and the latter is secured to the frame A by punching or indenting its side flanges so as to form eyelets or burrs within 25 the openings e.

In the foregoing description I have referred to the plate E as constituting the upperside of the frame A, but it is to be understood of course that this expression has reference only to the position in which the figures 30 appear in the drawings, it being obvious that any one of the four sides of the frame may be made in the form of the cap or cover plate E. If, as in Figs. 1 and 2, the end plate 35 instead of the side should be made of sheet metal, two parallel sides of frame A would of course be cast with grooves or channels.

In practice it is preferred to make contact or electrical connection with the resistance 40 through the frame A, which is ordinarily done through one of its end bars, as a in the accompanying drawings; but if desired, the conductor may be entirely insulated from the

frame and both its ends brought out in the same manner as the one end in Figs. 1 and 2. 45

I do not broadly claim herein a resistance device in which the conductor is formed of a flat metallic band or tape folded back and forth upon itself, nor, broadly, one composed of wire wound about an insulating body. 50

Having thus described my invention, what I claim is—

1. A resistance section, card, or block comprising a channeled open frame A, a coiled or folded conductor having its folds insulated from one another and mounted within said frame, and insulating material interposed between the conductor and the frame, substantially as described and shown. 55

2. A resistance card or section consisting of a frame A having a channeled bar b, a folded conductor B having its folds insulated one from another and inserted within the frame A, insulating strips D inclosing the ends of the conductor folds, and a removable 65 cap plate E applied to the frame and serving to retain the conductor therein.

3. In combination with a frame having openings d, a conductor mounted within said frame, and a separate cap plate E applied to 70 said frame and secured thereto by indenting or forcing the metal of its flanges into the openings d.

4. A resistance card, block, or section, comprising an open frame, a separate cap or bar applied to said frame and forming one wall thereof, and a conductor mounted within said frame and held in place by the detachable cap or bar, substantially as described and shown. 75

In witness whereof I hereunto set my hand in the presence of two witnesses.

ALTON J. SHAW.
